US0D1076801S

(12) **United States Design Patent** (10) **Patent No.:** **US D1,076,801 S**
(45) **Date of Patent:** **** May 27, 2025**

(54) **CHARGING BOX**

(71) Applicant: **Xiamen Retone Hearing Technology Co., Ltd.**, Xiamen (CN)

(72) Inventors: **Yiquan Shi**, Xiamen (CN);
Chengxiang Zhang, Xiamen (CN)

(73) Assignee: **Xiamen Retone Hearing Technology Co., Ltd.**, Xiamen (CN)

(**) Term: **15 Years**

(21) Appl. No.: **29/882,794**

(22) Filed: **Jan. 19, 2023**

(30) **Foreign Application Priority Data**

Sep. 29, 2022 (CN) 202230650444.5

(51) **LOC (15) Cl.** **13-02**

(52) **U.S. Cl.**

USPC **D13/108**; D3/294

(58) **Field of Classification Search**

USPC D13/103, 107, 108, 118, 119; D3/273, D3/274, 294, 295, 302; D14/205, 223, D14/229; D24/174

CPC . H02J 7/0044; H02J 7/0045; A45C 2011/001; B65D 43/16

See application file for complete search history.

(57) **CLAIM**

The ornamental design for a charging box, as shown and described.

DESCRIPTION

FIG. 1 is a perspective view of a charging box showing our new design;

FIG. 2 is a front view thereof;

FIG. 3 is a rear view thereof;

FIG. 4 is a left side view thereof, a right side view being a mirror image of the left side view;

FIG. 5 is a top view thereof;

FIG. 6 is a bottom view thereof; and,

FIG. 7 is a perspective side view thereof in an open configuration.

The broken lines depict portions of the charging box that form no part of the claimed design.

1 Claim, 7 Drawing Sheets
